[57] CLAIM

The ornamental design for a camera bag, as shown and described.

DESCRIPTION

FIG. 1 is a perspective view of a camera bag showing my new design, with one of the front pocket flaps raised;

FIG. 2 is a right side elevational view thereof, with the flaps closed;

FIG. 3 is a left side elevational view;

FIG. 4 is a front elevational view with the two zipper pulls of the concealed zipper arranged to protrude from the concealing flap;

FIG. 5 is a rear elevational view;

FIG. 6 is a top plan view;

FIG. 7 is a bottom plan view; and

FIG. 8 is a top perspective view with the top of the bag partially opened.
The partial showing of surface shading indicating a fabric texture is understood to be continuous on those surfaces where shown.FIG. 2
